FOREIGN PATENT DOCUMENTS

JP 1116271 S 7/2011

Primary Examiner — Marianne Pandozzi*Assistant Examiner* — Jae Liang(74) *Attorney, Agent, or Firm* — Polson Intellectual Property Law, PC; Margaret Polson**CLAIM**

The ornamental design for a travel mug, as shown and described.

DESCRIPTION

FIG. 1 is a top side perspective view of a travel mug in its open position showing my new design;

FIG. 2 is a bottom perspective view thereof;

FIG. 3 is a front view thereof;

FIG. 4 is a rear view thereof;

FIG. 5 is a left side view thereof; the right side view being a mirror image;

FIG. 6 is a top view thereof;

FIG. 7 is a bottom view thereof;

FIG. 8 is a front view of the travel mug in its closed position; and,

FIG. 9 is a side view thereof.

1 Claim, 6 Drawing Sheets---
